FASTENING MEANS FOR PAPER FOLDERS AND CONTAINERS

Filed July 12, 1921

UNITED STATES PATENT OFFICE.

WILLIAM R. SHRUM, OF PHILADELPHIA, PENNSYLVANIA, ASSIGNOR TO BROWN & BAILEY COMPANY, OF PHILADELPHIA, PENNSYLVANIA, A CORPORATION OF PENNSYLVANIA.

FASTENING MEANS FOR PAPER FOLDERS AND CONTAINERS.

Application filed July 12, 1921. Serial No. 484,065.

This invention relates to fastening means adapted for conveniently engaging and securely holding paper or fibre board folders and containers, including knock down boxes, 5 in assembled or erected form.

The characteristic features of the improvements are set out in the following description and the accompanying drawings in illustration thereof.

10 In the drawings, Fig. 1 is a plan view of a transversely scored paper or fibre board strip provided with my improved fastening means adapting the same to be used as a wrapper or band for holding, say, sheets 15 of material arranged in layers; Fig. 2 is a perspective view of the construction shown in Fig. 1 with the end members turned in and in process of engaging the locking parts; Fig. 3 is a plan view of a paper or 20 fibre board sheet having a form adapting it for use as a folder or container and provided with my improved locking means and Fig. 4 is a perspective view of the erected construction illustrated in Fig. 3 when in 25 process of engaging the locking parts.

In the form shown in Figs. 1 and 2, the construction comprises the integrally connected body or bottom and intermediate section 1, the parallel sections 2 connected therewith in hinged relation upon the score 30 lines 3 and the end sections 4 and 5 connected with the respective sections 2 in hinged relation upon the score lines 6.

The section 4 is provided with the transverse slot 7 having the inturned or hook-like ends 7' forming the end tongues 8.

The section 5 is provided with the dove-tail tongue and the reentrant loops or open circular holes 10 intersecting the angular 40 edges 5' and 9' between the body of the section 5 and the ends of the tongue 9. A score line 11 forms with the edges at one corner of the tongue, a triangular ear 12 adapted to be bent inwardly, so that the 45 distance along the outer end of the tongue can be substantially shortened and the tongue readily inserted through the slot 7, as by first entering the corner 13 therein followed by the complete entry of the tongue in 50 a single continuous operation. This results in the engagement of the eyes or open loops 10 in the ends of the slot 7, in which relation the tongue 9 is locked by the ear or hook

12, the corresponding tongue 8 engaging the hook. 55

While the preferred construction involves the use of the single ear or hook 12, it is practicable, if it should be desired for any reason, to form an ear or hook of the other corner of the tongue 9, to cooperate with 60 the second tongue 8 in holding the parts together in assembled relation.

In the form shown in the constructions of Figs. 3 and 4, a paper or fibre board sheet is provided with the body, bottom or median 65 section 14 limited by the scores 15 and 16 along which are hinged the end or side sections 17 and 18. Flaps 19 are connected in hinged relation to the sections 17 on the score lines 20 parallel to the lines 15. 70

A top or end section 21 is connected in hinged relation to a section 18 along the score line 22 parallel to the adjacent line 16, the part 21 having a slot 23 preferably terminating in the hooked or inturned ends 75 23' providing the tongues 24.

An end section 25, supplementary to the section 21, is hinged to a member 18 on the score line 22 parallel to the adjacent line 16 and is provided with a dove-tail tongue 26 80 having the open loops or eyes 27 intersected by the edges 25' and 26'. A score line 28 forms a triangular ear 29 of one corner of the tongue 26. This ear is turned in to facilitate the entry of the tongue into the slot 85 23 for effecting the locking engagement, the opposite corner 30 being first entered in the slot followed continuously by the full entry of the tongue and the engagement of the ear which springs outward automatically to 90 provide a hooked engagement. A tongue 24 engages under the ear or hook 29 to hold the lock more securely in the assembled relation. While it is generally not desirable to do this, the corner 30 may be bent back 95 similar to the corner 29 and act in cooperation with the corresponding tongue 24 to hold the parts together. It will be understood that while the unbroken corners 13 and 30 facilitate the entry of the respective dove-tails in locking position they also serve to 100 maintain the desired locking engagement by reason of their form and their retention in place by the correlated hooks 12 and 29.

It is to be understood that the folder and 105 container shown are merely by way of illus-

trations of applications of the lock or fastening means which are applicable to and intended for use with containers generally.

Having described my invention, I claim:

- 5 1. A folder, container, or the like comprising an integral body bent to form the bottom, sides and top of a package and having overlapping end members one of which is provided with a slot and the other of
- 10 which is provided with a dove-tail tongue passing through said slot and housed beneath said slotted member, said tongue and the member of which it forms a part having edges intersected by reentrant open loops extending inwardly from the intersection of
- 15 projections of said edges, said tongue having a hinged corner adapted to be bent to facilitate the entry of said tongue in said slot and to effect locking engagement between
- 20 the overlapping parts and form a continuous package cover.

2. A folder, container or the like having

overlapping members, one of which is provided with a slot having an inturned end forming a tongue and the other of which is provided with a dove-tail tongue with ends terminating in open eyes and a hinged corner adapted to be bent inwardly for facilitating the entry of said tongue second named in said slot and for engagement with said tongue first named.

3. A folder, container or the like having overlapping members, one of which is provided with a slot and the other of which is provided with a dove-tail tongue having the form of a truncated triangle and a single hinged corner for facilitating the entry of said tongue in said slot and locking the same therein, the free end of said tongue being housed under said slotted member.

In testimony whereof I have hereunto set my name this 28th day of June, 1921.

WILLIAM R. SHRUM.
